UNITED STATES PATENT OFFICE.

CHRISTIAN AUGUSTUS ALBRECHT, OF BERLIN, GERMANY, ASSIGNOR TO MERGEN-
THALER LINOTYPE COMPANY, A CORPORATION OF NEW YORK.

TYPOGRAPHICAL LINE-CASTING MACHINE.

1,107,505.

Specification of Letters Patent. Patented Aug. 18, 1914.

Application filed February 7, 1910. Serial No. 876,100.

To all whom it may concern:

Be it known that I, CHRISTIAN AUGUSTUS ALBRECHT, a citizen of the United States of America, at present residing at Chausseestrasse 23, Berlin, N. 4, in the Empire of Germany, have invented new and useful Improvements in Typographical Line-Casting Machines, of which the following is a specification.

16 This invention relates to typographical line casting machines particularly those employing matrices such as are used in the machines known commercially under the trade mark "Linotype".

18 In those machines the justification of the composed line effected before the casting, is ordinarily carried out in two stages, for reasons which are of no interest on the present occasion.

20 After the first of the just-named stages, the matrices, moved sidewise during that stage, have not yet reached their final position, and the line of matrices was pressed in vertical direction against a horizontal alining rib or ledge, in order to aline all their formative cavities into the same horizontal line. Then, without releasing the considerable pressure necessary for effecting this alinement, the second and final stage of the 25 justification took place. Owing to the maintenance of this pressure throughout the said second stage, considerable friction was presented, which greatly hampered the lateral movement of the matrices and, in many instances, prevented the line from being sufficiently expanded or properly justified; this resulted in spaces being left between adjacent matrices or matrices and spacers, which, although possibly insignificant in 30 themselves, were causative of so-called "hair-lines", with the result that frequently the formative cavities of the matrices were damaged and the said matrices had to be discarded and replaced by others. According 35 to the present invention, this inconvenience is avoided by causing the pressure which presses the line against the alining rib to be reduced or entirely discontinued before and during the second stage of the 40 justification, so as to facilitate the movement of the matrices during that said stage.

45 BY FRED. ALB.

In these drawings:—Figure 1 represents in sectional elevation, the mechanism in the position after the first justification and before the alining of the line, and Fig. 2 is a similar view representing the mechanism as 60 during the alinement of the line.

1 represents the casting mold carried, as ordinarily, on a mold wheel or carrier 2, 3 represents the first elevator head, 4 the matrices of the composed line, and 5 the cam operating the first elevator and fast upon shaft 6.

7 represents a bell-crank lever operated by the cam 5 through a roller 8 pivoted to the vertical arm of the said lever, and 9 represents a link connecting the lever 7 to the first elevator.

10 represents the space bars of the composed line, and 11 represents the justification bar, which, under the influence of a lever 12 75 and spring 13, forces the longer wedges of the space bars upward so as to tighten the composed line.

During the first justification, the cam roll 8 is in the depression 14 of the cam 5, 80 so that the first elevator, as shown in Fig. 1, remains in its lowermost position resting upon the top of the vise frame 15 which, as ordinarily, is connected with the fixed frame of the machine. In this position 85 there is a space 16 between the underside of the horizontal alining rib 17 on the mold 1 and the upper surface of the rear lower lugs 18 of the matrices 4. After the first justification, the cam 5 is turned so far in 90 the direction indicated by the arrow, as to bring its projection 19 against the roller 8 as shown in Fig. 2, thus raising the first elevator from the position indicated in Fig. 1 into that indicated in Fig. 2, thereby 95 pressing the upper surface of the matrix lugs 18, against the underside of the alining rib 17, and effecting the alinement in vertical direction of the several matrices of the composed line.

100 While, in existing arrangements, the projection 19 formed a large and uninterrupted part of the circumference of the cam, and was, throughout its length, concentric with the shaft 6, the said projection, in accordance with the present invention, is short, and is immediately followed by a depression 20, the dimensions of which are such, that the pressure, which serves to press the lugs 18 against the alining rib 17 as afore- 110

said, is reduced or entirely stopped throughout the second stage or justification, which takes place immediately thereafter and, with little or no friction, presented against the 5 lateral movement of the matrices.

The depth of the depression 20 may vary according to requirements; it is, however, preferably only of such depth that the pressure of the lugs 18 against the alining surface 10 face 17 is reduced without the lugs being moved out of actual contact with the said surface. The depression 20 is immediately followed by the rise 21 of the cam which again presses the matrix line firmly against 15 the alining rib and maintains this pressure during the casting operation.

22 represents the ordinary metal pot nozzle which constitutes no part of the present invention.

20 Having described my invention I declare that what I claim and desire to secure by Letters Patent is:—

1. In a typographical machine, the combination of a mold, justifying mechanism, 25 an elevator to carry the matrices to and from the mold and capable of a further movement to aline them with reference thereto, and a cam for imparting the aforesaid movements to the elevator, the said cam 30 being formed to effect a slight relaxation of the alining action during justification.

2. In a typographical machine, the combination of a mold justifying mechanism acting in two successive stages, an elevator to 35 carry the matrices to and from the mold and capable of a further movement to aline them with reference thereto, and a cam for imparting the aforesaid movements to the elevator, the said cam being formed with 40 two projecting portions to effect the alinement of the matrices in two successive

stages, one following each of the justifying stages, and with an intermediate depression to permit a relaxation of the alining pressure between such alining stages.

3. In a typographical machine, the combination of a mold justifying mechanism acting in two successive stages, a matrix carrier to present the matrices thereto and to aline the matrices in two successive stages, 50 one following each of the justifying stages, and a cam for moving the carrier, the said cam being formed on its periphery with two projecting portions which effect the alinement of the matrices in the aforesaid stages 55 and with an intermediate depression to permit a relaxation of the alining pressure between such alining stages.

4. In a typographical machine, the combination of a mold, a line of matrices to co-operate with the mold, mechanism for justifying the line in two successive stages, and means for alining the matrices against the mold between the two justifying stages, the said means being constructed to permit a 65 slight relaxation of the alining action during said stages.

5. In a typographical machine, the combination of a mold, a line of matrices to co-operate with the mold, mechanism for justifying the line in two successive stages, and means for alining the matrices against the mold after each justifying stage, the said means being constructed to permit a slight 70 relaxation of the alining action during said 75 stages.

In witness whereof I have hereunto set my hand in the presence of two witnesses.
